UNITED STATES PATENT OFFICE.

OTTO W. SIEBERT AND ORA N. TURNER, OF TEMPLETON, MASSACHUSETTS; SAID TURNER ASSIGNOR TO BAY STATE METAL WHEEL COMPANY, OF TEMPLETON, MASSACHUSETTS, A CORPORATION OF MAINE.

DESIGN FOR A BABY-CARRIAGE OR BASSINET CANOPY.

48,267.

Specification for Design.

Patented Dec. 7, 1915.

Application filed June 16, 1915. Serial No. 34,529. Term of patent 14 years.

To all whom it may concern:

Be it known that we, OTTO W. SIEBERT and ORA N. TURNER, citizens of the United States, residing at Templeton, in the county of Worcester and State of Massachusetts, have invented a new, original, and ornamental Design for a Baby-Carriage or Bassinet Canopy, of which the following is a specification, reference being had to the accompanying drawing, forming part thereof.

The figure is a perspective view of a bassinet canopy, showing our new design.

We claim:

The ornamental design for a baby-carriage or bassinet canopy, substantially as shown.

OTTO W. SIEBERT.
ORA N. TURNER.
